Filed Jan. 7, 1959, Ser. No. 785,430

2 Claims. (Cl. 131—256)

This invention concerns matchbooks, and more particularly matchbooks of the type having a portion which serves both as additional advertising space and as a snuffer for cigarettes.

Various devices have been proposed in the past for attachment to matchbooks for the purpose of holding and/or snuffing out cigarettes. All of these devices have had one or more disadvantages. For one, many of the prior art devices have been formed of metal and therefore were expensive and could not be produced as a part of the matchbook itself. For another, the snuffing attachments of the prior art held the cigarette in a firmly wedged relationship with the device, so that it was difficult to withdraw the cigarette, particularly if the butt was rather short. Also, the metal snuffer had a tendency to get quite hot, metal being a good conductor of heat, so as to be likely to cause injury to the user.

My invention overcomes all these difficulties by providing a snuffing tube at the narrow lower end of the matchbook which may be integrally formed with the matchbook cover itself and is closed at one end by a plug of cardboard or other material, or by other means. Further advantages of my invention will be readily appreciated from an inspection of the drawings in which:

Figure 1 is a perspective view of a matchbook constructed according to my invention;

Figure 2 is a partial vertical section of the matchbook, in the process of snuffing a cigarette; and

Figure 3 is a section along line 3—3 of Figure 2.

Basically, my invention consists in providing a cylindrical or quasi-cylindrical tube, of a diameter but slightly greater than that of a cigarette, at the narrow end of a matchbook remote from the sensitive ends of the matches. The tube may be formed by merely bending the lower end of the matchbook cover around a mandrel so as to form a tubular bulge therein before stapling it to the match pad. After the tube has been thus formed, a circular plug or disc of cardboard or other material is inserted in one end of the tube to substantially close it against the influx of air, and also to give it sufficient rigidity to retain its shape to a reasonable extent for the life of the matchbook. An airtight seal is not necessary between the plug and tube, so that the insertion of the plug presents no special manufacturing problems. A cigarette may be snuffed by turning the matchbook on its side, with the closed end pointing down, and dropping the cigarette into the opening of the tube. The combustion products of the cigarette (mainly carbon dioxide) accumulate rapidly near the closed end of the tube and snuff the cigarette due to lack of oxygen in a matter of a few seconds. In fact, the snuffing process is so fast that the inside of the snuffing tube does not scorch even though the lighted end of the cigarette rests against it. Consequently, and because of the poor heat conductivity of cardboard, the outside of the snuffing tube barely has time to get lukewarm, so that any chance of injury to the user is effectively prevented. Inasmuch as the diameter of the snuffing tube is somewhat greater than that of the cigarette, it is not

2

only easy to introduce the cigarette into the snuffing tube, but it is also easy to get the cigarette out again no matter how short the butt, merely by turning the matchbook upside down. Inasmuch as one end of the snuffing tube is substantially closed, the snuffing tube can also be used as a temporary ash tray. The presence of ashes in the snuffing tube will in no way impair its function, but on the contrary will improve its action by plugging up any tiny crevices at the closed end of the tube through which air might enter.

Referring now to the drawings, Figure 1 shows a perspective view of a matchbook constructed according to my invention. The matchbook 10 has a cover 12 made out of a single strip of cardboard, having an upper wider end 15 and a lower narrow end 16. A striking surface 18 is arranged in the usual way adjacent the lower end 16 of the cover 12, and the match pads 20 which tie together the lower ends of the matches 22 are stapled to the cover 12 by a staple 24 extending through both the front portion 25 and the rear portion 28 of the lower end of the cover 12. In conventional matchbooks, the lower end of cover 12 is, of course, merely folded around the bottom edge 30 of match pads 20. According to my invention, however, the cover 12 is formed into a tubular bulge 32 which is generally tangential to the lower edge 30 of match pads 20 as shown in Figure 3. Except for the tubular bulge 32 in the cover 12 at the bottom of the matchbook 10, the construction of the matchbook is quite conventional. The tube 32 formed by this bulge in the cover 12 is closed at 30 one end by a plug 34 but is open at the end 36.

Figure 2 shows a section of the snuffer with a cigarette butt deposited therein. Even though the plug 34 is by no means airtight, it obstructs the tube 32 to a sufficient degree that the combustion products of the cigarette 38 will rapidly accumulate in the end 40 of tube 32. In a matter of a very few seconds, these combustion products prevent oxygen from reaching the end 40 of tube 32, and the cigarette will therefore go out almost instantly. While I have not found it to be necessary, it will be understood that whenever an added precaution is deemed desirable 40 the interior of tube 32 may be coated with metal foil or otherwise treated to inhibit combustion. Inasmuch as no compressing of the ashes or of the cigarette is necessary to extinguish the cigarette, it can be removed and re-lit if desired without difficulty and without presenting a distasteful appearance. During the snuffing process, the matchbook is preferably turned so that the plug 34 faces down and the axis of the tube 32 is vertical. In order to remove the cigarette 38 after it is snuffed, or 45 in order to remove any ashes which may have been deposited in the tube 32, it is merely necessary to invert the matchbook.

Another feature of my invention is that the matchbook when in closed condition will readily stand on one side. When one is attempting to place the lit cigarette in the snuffer tube any accidental touching of the closure flap by the lit end of the cigarette will not ignite the matches within the book. It is not necessary to have the flap in open condition for supporting the book and snuffer tube in a vertical condition. Further with the matchbook and tube standing in a vertical condition and the flap closed the upper edge of the match book may be used as a guide to lead the user of the tube by virtue of the fact of feeling the gradual narrowing of the upper edge.

65 It will be readily seen that I have provided a simple, effective and safe cigarette snuffer and temporary ash tray which can be formed as a part of a matchbook during the manufacture thereof and is therefore extremely cheap to produce. Furthermore, the easy imprintability and large area of my cardboard snuffer make it particularly attractive to advertisers. The value of the additional ad-

vertising space, as well as the usefulness of my device far outweigh the insignificant extra cost, if any, of producing the matchbook of this invention as compared to a conventional matchbook.

Other methods of making my snuffer will readily suggest themselves to those skilled in the art without departing from the spirit of this invention. I therefore do not desire to be limited by the embodiment shown herein.

Having thus described the invention, what is claimed and desired to be secured by Letters Patent is:

1. The combination of a support and a snuffer tube, the support comprising a match book of the type having a body with one relatively wide end and a relatively narrow end when in closed condition, the snuffer tube comprising a cylindrical tube having a length coextensive with the width of the matchbook and integral with the narrow end, the vertical axis of the tube being in the major medial plane of the matchbook when the support and tube are standing on a side, means closing one end of the tube with the other end being open, the tube having an interior 20

5

10

cross-sectional area slightly larger than the cross-sectional area of a cigarette so as to receive a cigarette therein without binding, the configuration of the match book when standing on a side in closed condition acting as a guide means to lead the user to the snuffer tube.

2. The combination as set forth in claim 1 wherein the match book has one fixed side and a movable side serving as a cover for the matches and which is intended when closed to act as a protector for the matches against accidental contact with the burning end of a cigarette.
